US0D1087661S

(12) **United States Design Patent** (10) **Patent No.:** **US D1,087,661 S**
(45) **Date of Patent:** **** Aug. 12, 2025**

(54) **READING PILLOW**

(71) Applicant: **Hangzhou Yingmu Technology Co., Ltd.**, Hangzhou (CN)

(72) Inventor: **Hong Li**, Zhaotong (CN)

(73) Assignee: **Hangzhou Yingmu Technology Co., Ltd.**, Hangzhou (CN)

(**) Term: **15 Years**

(21) Appl. No.: **29/992,292**

(22) Filed: **Mar. 7, 2025**

(30) **Foreign Application Priority Data**

Sep. 7, 2024 (CN) 202430572560.9

(51) **LOC (15) Cl.** **06-09**

(52) **U.S. Cl.**

USPC **D6/601**

(58) **Field of Classification Search**

USPC D6/595, 596, 597, 601, 604, 716.4

CPC A47G 9/00; A47G 9/10; A47G 9/1009;

A47G 9/1027; A47G 9/1054; A47G

9/1072; A47G 9/1081; A47G 9/109;

A47G 2009/1018

See application file for complete search history.

(57) **CLAIM**

The ornamental design for a reading pillow, as shown and described.

DESCRIPTION

FIG. 1 is a front perspective view, showing my new design; FIG. 2 is a rear perspective view;

FIG. 3 is a front view;

FIG. 4 is a rear view;

FIG. 5 is a left side view;

FIG. 6 is a right side view;

FIG. 7 is a top view; and,

FIG. 8 is a bottom view.

1 Claim, 8 Drawing Sheets
